Primary Examiner — Sanjeev Paul

(57) **CLAIM**

The ornamental design for gemstone viewer, as shown and described.

DESCRIPTION

1. Gemstone viewer

1.1 : Perspective

1.2 : Top

1.3 : Front

1.4 : Right

1.5 : Back

1.6 : Left

1.7 : Bottom

1.8 : Perspective

The device for which the design right is sought, operates with smartphone camera to take photographs of gemstones; reproduction 1.1 is front perspective view of the gemstone viewer, showing claimed design; 1.2 is top view thereof; 1.3 is front view thereof; 1.4 is right view thereof; 1.5 is back

(Continued)

view thereof; 1.6 is left view thereof; 1.7 is bottom view thereof; 1.8 is rear perspective view thereof.

1 Claim, 8 Drawing Sheets
